(57) **CLAIM**

I claim, the ornamental design for a roller guide tip for use with fishing rods, as shown and described.

DESCRIPTION

FIG. 1 is a top plan view of a roller guide tip for a fishing rod showing my new design;

FIG. 2 is a right side elevational view thereof;

FIG. 3 is a bottom plan view thereof;

FIG. 4 is a front view thereof; and,

FIG. 5 is a rear view.

The left side of the illustrated base for the roller guide tip is not shown because it is a mirror image of the right side shown in FIG. 2.

Any broken line illustration in the drawing disclosure is not part of the design sought to be patented.
